US0D1103596S

(12) **United States Design Patent** (10) **Patent No.:** **US D1,103,596 S**
(45) **Date of Patent:** **** Dec. 2, 2025**

(54) **FOOTWEAR**

(71) Applicant: **MSCHF**, Brooklyn, NY (US)

(72) Inventors: **Lukas Bentel**, Astoria, NY (US); **Kevin Wiesner**, Long Island City, NY (US); **Gabriel Whaley**, New York, NY (US)

(73) Assignee: **MSCHF**, Brooklyn, NY (US)

(**) Term: **15 Years**

(21) Appl. No.: **29/911,684**

(22) Filed: **Sep. 7, 2023**

(51) **LOC (15) Cl.** **02-04**

(52) **U.S. Cl.**

USPC **D2/926**; D2/916; D2/919

(58) **Field of Classification Search**

(57) **CLAIM**

The ornamental design for footwear as shown and described.

DESCRIPTION

FIG. 1 is a top front perspective view of a footwear showing our new design;

FIG. 2 is a right elevation view thereof;

FIG. 3 is a left elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a bottom front perspective view thereof; and,

FIG. 9 is a top rear perspective view of an alternate open configuration thereof.

The evenly-spaced broken lines in FIGS. 1-6 and 8 illustrate stitching of the footwear and form part of the claimed design.

1 Claim, 8 Drawing Sheets
